CURVED PLATEN PRINTING PRESS

Joseph F. Jirousek, Cleveland, Ohio, assignor to
 The Chandler & Price Company, Cleveland,
 Ohio, a corporation of Ohio

Application May 27, 1946, Serial No. 672,631

5 Claims. (Cl. 101—297)

1

This invention relates, as indicated, to platen printing presses and more particularly to such presses in which a rolling contact is obtained between the sheet on the platen and the form. It has long been recognized (see U. S. Patent No. 1,034,083 to Clark, dated July 30, 1912) that there are certain advantages in cylinder presses over the Gordon or platen type press, including the fact that the sheet to be printed contacts the impression cylinder progressively with relatively little area in contact whereas in the conventional Gordon press the entire sheet carried on the platen receives the full impression from the form at one time. This calls for the application of a great deal of force and requires great strength and rigidity in the supporting elements of the press.

To the best of applicant's knowledge no platen press of a type affording rolling contact with the form has yet met with commercial success, largely due to failure to provide a mechanism sufficiently positive and precise in its action.

It is, therefore, a principal object of this invention to provide a platen printing press affording rolling contact of form and platen in a manner to effect a firm and consistently reproducible impression.

A further object is to provide a press of the indicated type capable of great impression strength but of relatively light construction.

Still another object is to provide a press of the indicated type which is capable of great rapidity of operation but nevertheless opens to an extent which facilitates feeding and delivery of sheets to and from the platen.

Other objects of my invention will appear as the description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a side elevational view of the upper portion of a platen press constructed in accordance with my invention, and Fig. 2 is a broken front elevational view of the same portion of the press.

Referring now more specifically to the drawings, the main frame 1 of the press supports the

form-bed 2 in which the usual chase and form (not shown) are adapted to be mounted. The frame is recessed at each side at 3 to permit the lower inking rollers 4 and 5 to move inwardly after their downward passage across the form whereby the upper inking roller 6 is enabled to completely traverse such form. Tracks 7 are provided for such rollers leading from a conventional fountain and distributing-disc (not shown).

Mounted on said main frame to each side of said form-bed are racks 8 extending downwardly from said form-bed except where interrupted by recess 3. A platen 9 having a convexly curved face 10 adapted to engage in rolling contact a form carried by said form-bed is provided with curved racks 11 along each side and extending downwardly therefrom. Said racks 11 on said platen are adapted to mesh with the racks 8 on the main frame of the press in cooperative engagement whereby precise positioning of the platen relative to the form-bed is obtained and preserved. The downwardly extending portions 12 of the platen 9 are more sharply curved than the sheet-supporting face 10 and the corresponding portions of racks 11 are likewise more sharply curved than in their upper portions. It will be seen therefore, that when the platen 9 is rocked to a closed position as shown in dash line in Fig. 1 the teeth of racks 8 and 11 will progressively mesh, recess 3 being bridged without difficulty, until rolling contact has been made with the entire face of the form. Because of the increased arcuity of the lower portions of racks 11 it will be seen, likewise as illustrated in Fig. 1, that the platen in open position may be caused to assume a substantially horizontal position, thereby greatly facilitating feeding and delivery operations. A support, such as wooden stop or rest 13, may be provided for said platen in open position.

To operate the press, gears 14 are keyed to shaft 15 which is journalled in main frame 1. It will be noted that similar driving means are provided on each side of the press (see Fig. 2). Journalled on said shaft 15 between gears 14 and main frame 1 are side members 16 rigidly connected to the main frame by studs 17 and bosses 18. In the outer surfaces of such side members 16 are cam-tracks 19, substantially circular except for sinuous portions in the region adjacent form-bed 2. Radially extending slide-ways 20 are rigidly mounted on the outer faces of gears 14 with the outer ends of said slide-ways 20 tending across cam-tracks 19. Cam-followers 21

adapted to travel in cam-tracks 19 are rotatably mounted in slides 22 in slide-ways 20 and pivotally connected to the ends of platen operating arms 23. The other ends of arms 23 are pivotally connected to the upper portion of the platen so that when gears 14 are rotated in a counter-clockwise direction as viewed in Fig. 1 by driving means not shown, said arms 23 will be given reciprocatory motion to open and close the press.

Journalled to cross-shaft 24 are depending arms 25, pivotally connected with the downwardly-extending portions 12 of the platen 9 by means of links 26. Rollers 27 mounted on arms 25 engage cams 28 keyed to shaft 15 so that as such shaft rotates and arms 23 are reciprocated arms 25 are likewise actuated, permitting downwardly extending portions 12 of the platen to move up and outwardly as shown in dash line in Fig. 1, but ensuring continuous meshing of the teeth of racks 8 and 11. The movement of the platen is thereby positively controlled and heavy pressure may be maintained during the impression since both upper and lower portions of the platen are operatively connected to the driving means.

Throw-off means may be provided similar to that disclosed in Johnson Patent No. 2,357,116, dated August 29, 1944, with shaft 15 journalled in an eccentric amount 29 rotatable through lever arm 30 and link 31, whereby the platen may be prevented from coming into impression engagement with the form as it oscillates.

From the foregoing the general operation of my new press is readily discernable. When slide-ways 20 have been carried around to the position illustrated in solid line in Fig. 1 it will be seen that followers 21 have entered the sinuous portions of cam-tracks 19 and no further motion is imparted to the platen until followers 21 pass beyond such sinuous portions, arms 23 having imparted thereto only an arcuate movement about their axis of pivotal attachment to the platen. This provides a dwell or rest period during which the printed sheet may be removed from the platen and another sheet fed thereto. As shown in Fig. 2, arms 23 are widely spaced and do not interfere with the usual feeding and delivery operations. It is during this period, also, that the inking rollers pass over the form. While arms 23 are shown as being upwardly bent such arms may be downwardly bent, for example, to facilitate access to the platen.

As gears 14 continue to turn, arms 23 draw the upper portion of the platen toward the form-bed, racks 11 meshing with racks 8 to impart a progressive rolling motion and cams 28, acting through arms 25 and links 26, controlling the upward and outward movement of the lower portion of the platen. A sheet carried on the platen receives the imprint of the form progressively until the platen has reached the position shown in dash line in Fig. 1. By this time slide 20 has reached the slight inward bend of the cam-track and begun to move toward the form-bed again as gear 14 continues to turn and the press is opened, platen 9 being rocked back to the solid line (dwell) position. To avoid possibility of a double impression, just as arms 23 begin to swing the upper portion of the platen outwardly the above-described throw-off means comprising eccentric journal 29 is rotated through arm 30 and link 31 sufficiently to move shaft 15 and the parts carried thereby slightly toward form-bed 2 so that the entire platen is moved outwardly a fraction of an inch to avoid possibility of a

double impression as the press is opened but insufficiently to take racks 8 and 11 entirely out of mesh. Such actuation of the throw-off mechanism is normal to the operation of the press. The throw-off is also adapted to be actuated throughout the complete cycle in any conventional manner in case of emergency, for example. In normal operation, when the platen has rocked to a position where it would no longer contact the form, the throw-off mechanism operates to again cause tight enmeshment of racks 8 and 11. Tension springs 32 acting on arms 25 act to hold rollers 27 in close contact with cams 28 even when the throw-off is operative.

It will be noted that during the printing operation a firm rolling contact is obtained without any sliding or resilient mounting of the positioning means so that great precision and reproducibility of impression are obtainable. Of course, if desired, the positions of the platen and the form-bed may be reversed and the form-bed or both form-bed and platen, provided with a curved surface for rolling contact, although a preferred form is illustrated and described herein. Likewise, it is possible to provide the curved platen with substantially straight rack means and curve the rack means on the main frame to obtain the desired movement.

Other modes of applying the principle of the invention may be employed, change being made as regards the details described, provided the features stated in any of the following claims or the equivalent of such be employed.

I therefore particularly point out and distinctly claim as my invention:

1. In a platen printing press of the character described, a main frame, a form-bed carried by said frame, a platen having a convexly curved surface adapted to make rolling contact with a form in said form-bed when oscillated into impression position, rack means on said frame to each side of said form-bed, convexly curved downwardly extending portions of said platen, rack means on said platen to each side of the impression surface of said platen and continuing along said downwardly extending portions, said rack means on said platen meshing with said rack means on said frame to position said platen relative to said form-bed, a shaft rotatably journalled in said frame on an axis parallel to said form-bed, means for rotating said shaft, a slide mounted radially of said shaft and rotatable therewith, an arm pivotally connected to said slide and to the upper portion of said platen operative to oscillate said platen when said shaft is rotated, a continuous cam track on said frame, a cam follower on said slide engaging said cam track to control the reciprocation of said arm, an arm pivotally connected to said frame, a link pivotally connecting said arm and a said downwardly extending portion of said platen, and cam means on said shaft engaging said last-named arm operative in conjunction with said rack means to control the oscillation of the said downwardly extending portion of said platen and maintain said rack means in meshing engagement.

2. In a platen printing press of the character described, a form-bed, rack means to each side of said form-bed, a platen having a uniformly slightly convexly curved impression surface for rolling contact with a form carried in said form-bed, such curve having a relatively long radius, convexly curved rack means on each side of said

platens and extending downwardly therefrom, the downwardly extending portions of said last-named rack means having a shorter radius of curvature than the portions to either side of the impression surface portion of said platen, said rack means to each side of said form-bed likewise extending downwardly below said form-bed, and means for maintaining said rack means in meshing engagement.

3. In a platen printing press having a main frame and a form-bed carried by such frame; a curved platen oscillatorily mounted for rolling contact with a form carried in such form-bed, rack means on said platen and rack means on such frame extending below such form-bed in mesh with said first-named rack means, inking rollers operative to travel vertically across a form carried in such form-bed, and a recess in such frame below such form-bed to receive at least certain of said rollers at the conclusion of their downward traverse, said rack means on such frame being interrupted by said recess but continued therebelow to engage the said rack means on said platen when said platen is in open position, and said rack means on said platen below the point of contacting position between such form-bed and said platen having a curvature of relatively shorter radius adapted to span said recess in said rack means on said frame while maintaining constant engagement with said latter rack means.

4. In a platen printing press of the character described, a main frame, a form-bed carried by said frame, a platen having a convexly curved surface adapted to make rolling contact with a form in said form-bed when oscillated into impression position, rack means mounted on said frame to each side of said form-bed, rack means mounted on said platen to each side of the impression surface of said platen in mesh with said rack means on said frame, driving means on said frame, paired arms pivotally connected to the upper portion of said platen and adapted to be reciprocated by said driving means to oscillate said platen into and out of impression position, and arms pivotally connected to the lower portion of said platen, control means operative positively to regulate movement of said latter arms to maintain said rack means at all times in meshing engagement as said platen oscillates, and means automatically operative during opening movement of the press to shift said drive means

and paired arms correspondingly to move said platen away from such form-bed a distance sufficient to avoid double impression while maintaining continued meshing of said rack means, said rack means on said platen extending downwardly therefrom continuously in mesh with said first-named rack means, one of said pairs of rack means having a curvature of reduced radius in the region below said form-bed and platen to accelerate opening movement of said platen after completion of the impression.

5. In a platen printing press having a main frame and a form-bed carried by such frame; a platen, having an impression surface, mounted for oscillatory movement relative to such form-bed and frame and having a convexly curved portion in constant engagement with such frame, and adapted to engage such frame at a point spaced below such form-bed when said platen is in open position, rack means mounted on said frame to each side of said form-bed and rack means mounted on said platen to each side of said impression surface, inking rollers operative to travel vertically across a form carried in such form-bed, means for causing said inking rollers to travel in timed relation to the opening and closing of the press, and a recess in such frame, between the lower edge of such form-bed and the point where said platen contacts such frame when in open position, adapted to receive at least certain of said rollers at the conclusion of their downward traverse.
